[57] CLAIM

The ornamental design for a photographic print paper magazine with multi-position handle, substantially as shown.

DESCRIPTION

FIG. 1 is a top and left front perspective view of a photographic print paper magazine with multi-position handle showing our new design;

FIG. 2 is a top plan view thereof;

FIG. 3 is a left side elevational view thereof;

FIG. 4 is a front elevational view thereof;

FIG. 5 is a right side elevational view thereof;

FIG. 6 is a bottom plan view thereof;

FIG. 7 is a rear elevational view thereof;

FIG. 8 is a fragmentary view of the handle portion shown on an enlarged scale;

FIG. 9 is a top and front perspective view thereof with the handle in the open position.
